UNITED STATES PATENT OFFICE.

FREDRICK C. ASCHENBRENER, OF CHICAGO, ILLINOIS, ASSIGNOR OF ONE-FOURTH TO HIMSELF, ONE-HALF TO JOSEPH C. SEYL, AND ONE-FOURTH TO OSCAR H. E. FRITZ, ALL OF CHICAGO, ILLINOIS.

INCANDESCENT-LAMP SOCKET.

948,754.

Specification of Letters Patent.

Patented Feb. 8, 1910.

Application filed February 27, 1909. Serial No. 480,377.

To all whom it may concern:

Be it known that I, FREDRICK C. ASCHENBRENER, a citizen of the United States, residing at Chicago, in the county of Cook and State of Illinois, have invented certain new and useful Improvements in Incandescent Lamp Sockets, of which the following is a specification, reference being had to the accompanying drawings.

10 My invention relates to incandescent lamp sockets, and has particularly to do with sockets provided with a single pull cord for turning the light on and off.

It has for its object to provide an improved and simplified construction by which the number of parts will be greatly reduced and the construction in other respects simplified, strengthened and cheapened. I accomplish this object as illustrated in the drawings and as hereinafter described.

What I regard as new is set forth in the claim.

In the accompanying drawings,—Figure 1 is a partial sectional view of my improved socket; Fig. 2 is a perspective view of the body or support in or on which the several operating parts of the device are mounted; Fig. 3 is a perspective view showing the main pivot or shaft illustrating the manner in which the main operating spring is mounted; Fig. 4 is a perspective view of the ratchet-wheel; Fig. 5 is a view showing the other side of the ratchet-wheel; Fig. 6 is a perspective view of the pulley; Fig. 7 is a plan view of the body or support; Fig. 8 is a sectional view of the base; and Fig. 9 is a partial sectional view, taken at right angles to that shown in Fig. 8.

Referring to the drawings,—8 indicates 40 the body or support, which, generally speaking, is cylindrical in form and is made of porcelain, fiber, or any other suitable non-conductor. The body 8 is adapted to be inclosed in the usual metallic shell 9 provided 45 with the usual removable cap-piece 10, as shown in Fig. 1. It is also provided at its lower end with the usual brass screw-threaded socket 11 into which the incandescent bulb is screwed in the usual way.

50 12 indicates a pulley, which is mounted in the body 8 in a vertical position, being supported by a horizontal pivot or shaft 13 suitably secured in the body, as best shown in Fig. 9.

14 indicates a nut screwed upon the end of 55 the pivot 13 to hold it in position.

15 indicates a coiled spring, one end of which is secured to the pulley 12, its other end being fitted in a slot in the head of the pivot 13, as shown in Fig. 3. Said spring 60 serves to return the pulley 12 to its normal position after each operation thereof.

16 indicates a chain, which extends around the pulley 12 and is connected thereto at one end, as shown at 17 in Fig. 1. The chain 16 65 extends over the upper portion of the pulley, thence around over the lower portion thereof and out through a tubular opening 18 in the shell 9, as shown in Fig. 1. Thus by pulling down on the chain 16 the pulley 70 12 may be rotated, and after being so rotated is returned to its normal position by the spring 15. At one side the pulley 12 is provided with a projecting pin 19 which moves between lugs 20—21 in a plate 22 75 which is secured to the body 8, as shown in Figs. 1 and 2, said lugs serving as limit stops to prevent excessive rotation of said pulley.

23 indicates a ratchet-wheel, which is also 80 a switch, and serves to make and break the circuit between the line wires and the lamp. Said ratchet-wheel is constructed as shown in Figs. 4 and 5. At one side thereof it is provided with ratchet-teeth 24, preferably 85 four in number, which are arranged around the axis of said ratchet-wheel. Said ratchet-wheel fits upon the pivot 13 at one side of the pulley 12, the latter being provided with a spring-pawl 25 which projects laterally and 90 is adapted to engage the ratchet-teeth 24, the arrangement being such that when the chain 16 is pulled down the rotation of the pulley 12 thereby effected causes the ratchet-wheel 95 23 to rotate through an arc of ninety degrees. 95 The return movement of the pulley 12, however, does not rotate the ratchet-wheel, which is held against reverse rotation by a spring-pawl 26 best shown in Figs. 2 and 8. Said pawl is mounted upon a pin 27 suitably secured in the upper portion of the body 8, as shown in Figs. 2 and 8, in position to project down against and engage the periphery of the ratchet-wheel 23, as indicated in Fig. 1.

The pawl is best made by bending a piece of 100 brass, or other suitable material, immediately and placing the pivot at the bend of the metal, thus providing an arm 28 which

bears against the upper portion of the body and serves to hold the pawl 26 under tension and press it close against the periphery of the ratchet-wheel 23. As shown in Figs. 4 and 5, the periphery of the ratchet-wheel 23 is provided with four ratchet-teeth 29, through the engagement of which with the pawl 26, as above suggested, the ratchet-wheel 23 is held against reverse rotation.

10 30 indicates two segmental contact plates secured upon the periphery of the ratchet-wheel 23 at diametrically opposite points. Said plates extend through arcs of about ninety degrees so that they cover the periphery of the ratchet-wheel between successive ratchet-teeth 29. That portion of the periphery of the ratchet-wheel between the plates 30 is a non-conductor, preferably the upper portion of the wheel being made of a fiber, or other suitable nonconductor, the contact plates 30 being of brass, or other suitable conducting material, which is secured to the wheel. The plates 30 are connected together by a metallic ring 31 fitted 25 against the side of the ratchet-wheel 23 opposite the ratchet-teeth 24, as shown in Fig. 5. Said ring is preferably integral with the plates 30, as shown in Fig. 5, and serves as a means of connecting the plates 30 with one 30 of the poles of the lamp through a contact plate 32 best shown in Figs. 2 and 8. Said plate 32 is made of spring brass, or other suitable conductor, and is secured at its lower end to the body 8 by a screw 33 which also 35 serves to connect the lamp socket 11 thereto—said screw forming one of the contact pieces for the lamp in the usual way. As shown in Fig. 8, it is insulated from the brass socket 11 by a piece of mica 34, or other suitable 40 material, in the usual way. Thus the brass socket 11 forms one of the contact pieces of the lamp and the screw 33 forms the other. The upper end of the plate 32 extends up to and around the pivot 13, having a hole 35 therein through which said pivot passes. The upper end of said plate 32 is not secured directly to the body 8, but stands out a short distance from the body so as to bear against the plate 31 of the ratchet-wheel 23, as best 45 shown in Fig. 9. By this construction the plate 32 is always held yieldingly in contact with the disk 31 and is in electrical connec-

tion with the contact plates 30 of the ratchet-wheel 23.

35^a indicates a binding-post for a line-wire 55 36. Said binding-post is electrically connected with a screw 27 through a metallic plate 37. 38 indicates a second binding-post for the other line-wire 39, said binding-post being connected by a plate 40 and fuse 41 with the plate 22 and through it with the screw-socket 11 by a screw 42.

From the foregoing description it will be seen that when the spring contact pawl 26 bears upon one of the plates 30 of the ratchet-wheel 23 the binding-post 35 is connected with the screw contact 33 through said pawl 26, the contact plates 30, the disk 31 and plate 32. When, however, the pawl 26 is in contact with one of the nonconducting segments of the wheel 23 the contact point 35 is not in electrical connection with the screw contact 33—the circuit then being broken through the lamp. It will be obvious, therefore, that by rotating the pulley 12 by means 70 of the chain 16 the circuit through the lamp may be closed or opened as desired.

While my improved socket is intended primarily to have the lamp secured directly thereto as a part thereof, it will be understood that that portion which holds the lamp may be omitted and the socket used as a wall or general snap switch, and the claim hereinafter made is, therefore, to be construed accordingly.

That which I claim as my invention, and desire to secure by Letters Patent, is,—

An incandescent-lamp socket, comprising a body, a pivot mounted therein, a pulley mounted on said pivot, a disk mounted on 90 said pivot adjacent to said pulley and having conducting and non-conducting segments, ratchet mechanism between said pulley and said disk for rotating said disk from said pulley when the pulley is rotated in one 95 direction, a stop-plate secured to the body and having stops for limiting the rotation of said pulley, and a pin carried by said pulley and engaging said stops.

FREDRICK C. ASCHENBRENER.
